UNITED STATES PATENT OFFICE

BRUNO BAUER, OF VIENNA, AUSTRIA

CONSTRUCTION OF THE EXPANSION JOINT OF REINFORCED CONCRETE STRUCTURES

Application filed December 27, 1928, Serial No. 328,646, and in Austria January 3, 1928.

This invention relates to improvements in the construction of an expansion joint for reinforced concrete structures.

It is well known to arrange pile-bearings in the expansion joints of reinforced concrete structures but none of these constructions is satisfactory, mainly because the expansion joint passes through the pile-bearings without being afforded proper protection and without permitting complete inspection thereof.

The object of the present invention is to provide a pile-bearing which will be efficient in operation and which will not permit the individual parts to change their shape, and I accomplish this object by arranging the pile-bearing at the side of the joint and at the place of expansion, and by closing all sides thereof on the outside, and further by rendering the casing of the pile-bearing accessible from the exterior in order to permit the ready inspection of the bearing.

The invention is described in the following specification, set forth in the appended claim and illustratively exemplified in the accompanying drawings, in which,—

Fig. 1 shows a sectional elevational view of the connection between two beams having a pile-bearing.

Figs. 2 and 3 illustrate the pile-bearing in transverse section and longitudinal section, respectively.

Fig. 4 is a further sectional view of the pile-bearing.

Referring to the drawings, *a* and *b* denote the top and bottom bearing-plates respectively, and *c* and *d* the piles which are disposed to support four walls *e*, *f*, *g* and *h*, forming a box-shaped enclosure. The supports *c* and *d* are dimensioned according to the arising bearing-pressure and are shaped in the manner well known in bridge-building. The pile-bearing is completed by screwing the side-walls *g* and *h* to the bearing plates *a* and *b* as well as to the front walls *e* and *f* secured thereto, and into the concrete casing is arranged a rigid prismatic member, closed at all sides and embedded in concrete, thus avoiding the danger, of the bearing being rendered useless by the penetration

of concrete. The walls *g* and *h* are removable after dismantling the beams.

Filling members *i* and *k*, extend upwardly and downwardly from the bearing, with the advantage that the joint can be produced in the construction without any difficulty, and the width may be determined by calculation. At a later stage, the filling members prevent the obstruction of the joint, but practically do not resist the closing of the joint caused by the lengthwise expansion of the beam. This is attained by bending upwardly the ends of the sheet metal plates *i* and *k* to form beads *m*, *n*, *o*, *p*, *q* and *r* in the desired strength of the expansion joint and further the plates *i* and *k* are provided with curves or springs *l* along a number of the plates.

I claim—

A bearing between the abutting overlapping ends of beams forming the expansion joint of reinforced concrete structures comprising a casing closed at all sides and including spaced top and bottom walls interposed between the overlapping ends of said joint and laterally removable side walls, and upright pillars forming the bearings arranged in pendulous position within said casing.

In testimony whereof I affix my signature.

DR. BRUNO BAUER.
